UNITED STATES PATENT OFFICE.

EDGAR B. BICKER, OF ST. LOUIS, MISSOURI.

SELF-CLOSING CONTAINER.

1,274,374.

Specification of Letters Patent.

Patented Aug. 6, 1918.

Application filed January 18, 1917. Serial No. 142,995.

To all whom it may concern:

Be it known that I, EDGAR B. BICKER, a citizen of the United States, and resident of St. Louis, Missouri, have invented certain new and useful Improvements in Self-Closing Containers, of which the following is a specification containing a full, clear, and exact description, reference being had to the accompanying drawings, forming a part hereof.

My invention relates to improvements in self closing containers, wherein an open seam is provided in a flexible and elastic body which is normally closed against leakage of the contents of the container, and which seam, when the body of the container is distorted, will open to permit a discharge of its contents.

My object is to construct a simple and easily operated container of inexpensive construction which by distortion will open a normally closed seam and which upon a relaxing of pressure will by the elasticity of the body, restore the container to its normal shape and close its open seam to prevent leakage of its contents.

With the above, and other objects which will be hereinafter made clear, in view my invention consists in the novel construction, arrangement and combination of parts which will be fully, clearly and concisely set forth in my specification, pointed out in my claims and illustrated by the accompanying drawing, in which:

Figure 1 is a side elevation of a container especially designed for tobacco in form, for use in connection with pipes and cigarettes.

Fig. 2 is an edge view of the container.

Fig. 3 is a sectional plan taken on the line 40 3—3 of Fig. 1.

Fig. 4 is a plan of the container showing the same distorted to permit a discharge of its contents.

Fig. 5 is a plan of the blank, from which the body of the container is formed.

Fig. 6 is an inverted plan showing the folds in the exterior wrapper or label for the container, and

Fig. 7 is an enlarged fragmental, vertical, 50 sectional elevation of a portion of the body portion and top of the container.

The blank shown in Fig. 5 is a single piece of sheet material and may be formed of tin, paper, celluloid or other like elastic material, and the blank illustrated forms a con-

tainer whose cross section is an oblong having parallel sides and rounded ends; this being the most convenient form of container for pocket cans of smoking tobacco. The body portion of the blank is substantially of rectangular oblong shape, its middle portion 60 8 constituting the front of the container, its end portions 9 constituting the back of the container which are folded over the front and overlapped and their ends united in 65 various manners according to the material from which they are formed; that is, by gluing, soldering, welding or otherwise.

The dotted lines 10 in Fig. 5 show the folding lines forming the rounded ends 11, 70 11 connecting the front and back of the container. Along the upper margin of the blank there are the flaps 12, 12 which are of less length than the width of the container, and as clearly shown in Fig. 4, are brought to relative registration when the body is folded and the ends of the blank united as described. These flaps are then folded at an angle of ninety degrees and form a top 75 or lid only partially closing the upper end 80 of the container.

In this condition it is to be understood that the flaps are connected with the container along one margin only, their opposite margin being free from the upper margin 85 of the body of the container along the entire front and both ends. I retain the top or lid of the can, namely the flaps 12, in their folded positions by means of a flexible adhesive tape 13, extended across the flaps and 90 along the rounded ends of the container as clearly shown in Fig. 7.

The front of the container next its upper margin is provided with a notch 14 which, as will be made clear, provides for a large 95 pouring spout or discharge opening. As shown in Fig. 5, the central portion 8 of the blank or the front of the container carries an integral flap 15, whose ends are rounded to conform with the round ends of the container and which when folded at an angle of ninety degrees forms a complete closure for the bottom of the container, and which bottom is held in place in a manner to be described hereinafter.

The container, of course, may be employed without a lining, but in order to preserve smoking tobacco, both as to aroma and moisture, I prefer to employ a lining 16 preferably formed from material such as paraffin 110

paper and which is formed to substantially the shape of the container, and slipped end-
wise thereinto, its upper end being open and its lower end closed.

- 5 In order to hold the bottom 15 in proper position, I employ an outside wrapper or label 17 which is applied by adhesive after the container has been filled to conform with the container in its entirety except, of course, a seam 18 in said wrapper coinciding with the seam formed by the upper margin of the front of the container, and the front margins of the flaps 12 constituting the top of the container.
- 15 This wrapper, as well as the lining 16, extends across the notch 14 and being of greater flexibility than the material of the container may be distorted to a greater extent than the body of the container and thereby provide a relatively large pouring spout. In order to provide for a maximum of elasticity at the discharge end of the container, I provide an elastic band 19 of metal or whale bone and by preference secure the band next 20 to the body of the container by folding a part of the wrapper or label 17 over the band and adhesively securing the wrapper end to the inside face of the container around the band.
- 25 30 It will be apparent from this description and drawing that I have provided a container or tobacco can that will be normally closed, thereby preserving the aroma and moisture of the tobacco, as well as to prevent leakage and waste, and when it is desired to withdraw some of the tobacco the user need only grasp the top of the can between his thumb and index finger and compress the ends or rounded portions of the can which 35
- 40 act distorts the front of the can and opens the seam between the top margin of the front of the can and the lid, and that upon a relaxing of the pressure exerted by the thumb and finger the inherent elastic qualities of the container or the elastic band, will 45 restore the container body to its original position and shape, closing said seam.

It will be further apparent that, due to the flaps 12 being integrally connected with 50 the margins of the back portions of the container and turned at a right angle thereto, the said back of the container, next its top, will have little or no flexure, and that when pressure is applied to discharge contents 55 from the container the back and lid will be relatively immovable and that said pres-

sure will flex only the upper end of the front of the container.

Having thus described my invention, what I claim is:

- 60 1. A container comprising a body portion having integrally formed folding flaps arranged to form the ends of the container, means for holding the bottom end flap to completely close the bottom of the container, 65 means for holding the top end flaps to partially close the top of the container, the said top end flaps being detached along one side of the container to form an open seam between said side of the container and said 70 flaps, and an elastic element secured to the container body adjacent the top end thereof.
2. A container comprising a body portion, said body portion provided with a bottom end flap adapted to completely close the 75 lower end of the container and two top end flaps adapted to partially close the top end of the container, means attached to the body portion and the two flaps for holding the same in the desired position, a side of said body 80 portion being detached from the top end flaps thus affording means to empty the container without slitting the same, a lining for said container, an elastic band secured to the container adjacent its top end, and a 85 wrapper for said container a portion of the top edge of the same being detached from the top of the container.
3. A container comprising a body portion formed from a single piece of material and 90 provided with a single bottom end flap adapted to completely close the lower end of the container, and with two top end flaps adapted to partially close the upper end of the container, means for securing the upper 95 end flaps in the proper position and leaving one side of the container detached from the top end flaps, there being a notch formed in the side of the container adjacent the free ends of the top end flaps, and a lining for 100 said container projecting over the recess formed in the side of the container, thus providing a pouring spout for the contents of the container.

In testimony whereof, I have signed my 105 name to this specification, in presence of two subscribing witnesses.

EDGAR B. BICKER.
